DRYING APPARATUS

Alfred R. Smith, Forest Hills, N. Y., assignor to
Combustion Engineering Company, Inc., New
York, N. Y.

Application April 13, 1938, Serial No. 201,681

5 Claims. (Cl. 34—34)

This invention relates to systems for drying wet materials and has for its purpose the provision of certain improved features in one type of apparatus used for this purpose.

5 A statement of what the improved features are will be postponed until a description of the apparatus generally has been given.

In the following specification reference will be made to the accompanying drawings, the three figures of which show schematically three installations embodying the invention, Fig. 1 showing it in one form, and Figs. 2 and 3 showing it each in a varied form.

Referring first to Fig. 1, the material to be dried is fed into a drying tower 1 through a pipe 2. Hot gases from the furnace 3 are led to the drying tower 1 through a pipe connection 5. The material to be treated passes downward through the tower 1 together with the drying gases and reaches the disintegrating mill 7 where the material is agitated and comminuted and where the principal part of the drying operation occurs. The mill is driven by any desired means such as the motor 9. The comminuted material together with the drying gases and the moisture evaporated from the material leave the mill 7 and are conducted by conduit 11 to the cyclone separator 13. Here the solids are separated out, collecting at the lower end of the cyclone, the gases, substantially cleared of solids, being carried off through the connection 15, to a fan 17, which forces them through duct 19 to a point of disposal. The solids separated out are taken off through the outlet 21.

35 Raw material for treatment is brought in through the connection 23 from the hopper 24. The installation illustrated is adapted particularly to drying very wet materials. Such materials present some difficulties in handling, which difficulties are, in accordance with prior practice, overcome by admixing a certain amount of previously dried material with the incoming raw material. In accordance with this prior practice, the connection 25 from outlet 21 carries to the mixer 27 the required portion of the dried material, the portion not required being discharged through branch 29. Damper 31 makes it possible to divide the dried material in the desired ratio. The dried material is thoroughly mingled with 50 the raw wet material in the mixer-conveyor 27 and the mixture is discharged by the conveyor into pipe 2.

During the evaporation of the moisture, the temperature of the gases brought in through pipe 5 falls and additional hot gases are continuously

supplied through the pipe 5. This means that a corresponding amount of gases must be discharged at some point from the system. In addition, the moisture evaporated increases the amount of gases and this excess must also be discharged.

The gases to be vented may in some cases be discharged directly to the atmosphere. At 33 is shown a vent to atmosphere for this purpose, the vent being equipped with damper 34. At the point where the material is fed into the delivery pipe 2, there has heretofore inevitably been some leakage of gases. Either air leaks in, in indefinite, uncontrolled amounts, or gases leak outward from the system making it uncomfortable or impossible to work in the vicinity of the feeding device.

One of the main objects of my invention is to obviate this difficulty and this is accomplished by providing means to keep the pressure in the feeding device adjacent to the inlet to pipe 2 at 20 or substantially at atmosphere. For this purpose I provide a branch connection 37 from pipe 19 to the interior of the casing of mixer 27. This branch is equipped with a damper 39 and a damper 41 is also provided in pipe 2.

By this provision a number of advantageous features are obtained, including the removal of the difficulty mentioned. Primarily, outward leakage can be prevented entirely and at the same time the amount of air leakage into the system at this point can be minimized. In addition, dust carried by gases leaving the separator through pipe 15 is by the improvement partly saved instead of being lost by discharge into the air or to the furnace. To discharge such dust to the air is usually 35 objectionable and to discharge it to the air or deliver it to the furnace is wasteful where the dust is of any value. To the extent that it is saved and reclaimed, the invention has a beneficial effect in addition to the main one first mentioned. The arrangement also has the great advantage that it makes it possible, as explained more fully below, to regulate the amount of hot gases taken from the furnace without having a damper in pipe 5 where such damper will rapidly deteriorate on 40 account of the high temperature.

The operation of the new arrangement, in accomplishing these results, may be described a little more fully.

The fan 17 causes a sub-atmospheric pressure 50 in cyclone-separator 13, which extends back through pipe 11 and disintegrator 7 to drying tower 1 and pipe 2. On its outlet side, the fan creates a pressure above atmosphere in pipes 19 and 37. Obviously, by a proper setting of damp- 55

ers 39 and 41, primarily the former, a pressure equal to atmospheric or slightly above or slightly below, can be obtained in the mixer casing 27. Preferably the pressure is made slightly sub-atmospheric, so that there is no escape at this point of gases and dust, but only a slight inward leakage of air.

To regulate the amount of hot gases taken from furnace 3 through pipe 5, damper 41 is 10 suitably adjusted. Thus, if the gases coming from the cyclone are too hot, so that their discharge would entail waste of useful heat, and it is therefore desired to cut down the hot gas supply coming from the furnace, damper 41 is moved 15 toward its open position. This will tend to suck in air through the openings from the atmosphere into the casing 27, and to complete the setting, damper 39 is also moved far enough toward its wide-open position to maintain or to re-establish 20 the slightly sub-atmospheric pressure in the casing 27. Gases will then be drawn away faster from 19 and 37, and as a result less gases will be drawn in through 5. Conversely, if the gases from the separator are too cool, dampers 41 and 25 39 are moved in a direction toward their closed position, thereby causing less gas to be withdrawn from 19 and 37 and more to be taken in through 5.

Preferably this adjustment is made automatically, and for this purpose the following apparatus 30 is provided. At 19 there is arranged the bulb element 43 of a thermostatic control connected by 45 to the element 47 actuating damper 41. Any suitable thermostatic control may be employed, which will open and close damper 41 35 by the right amount responsively to temperature variations in the gases.

To keep the pressure in 27 at the desired point, pressure responsive means 51, subject to the pressure in 27, are employed, acting through connection 49 and actuating means 53 to set the damper 39 to maintain the desired pressure in 27.

The usual means, such as thermostat 55, controlling the fuel and air supplied to the furnace, are used to hold the temperature of the gases 45 passing through pipe 5 constant.

In Fig. 2 is shown a variation of the form of the invention from that described above. This variation consists in the addition of pipe 61, branching off from 37 and extending to pipe 5. 50 In this pipe is a damper 63 actuated by thermostatic means 65 responsively to temperatures at the fan outlet. This damper acts like damper 41 described above to regulate the amount of gases taken off the furnace through pipe 5. In 55 the form of Fig. 1 all the gases, which are to be recirculated, are passed through the conveyor-mixer housing. The form of Fig. 2 is used in cases where the amount of the recirculated gases is too large for this, or where for some other 60 reason it is undesirable to send all these gases through the casing. The dampers 39 and 41 in pipes 37 and 2 are used as heretofore, but the by-pass 61 takes care of the greater part of the recirculated gases.

65 In some instances it will be necessary or desirable to deodorize all gases before discharging them to the atmosphere. An arrangement for this purpose embodying my invention is shown

in Fig. 3. The arrangement is quite similar to that of Fig. 1, but instead of discharging excess gases to atmosphere by means of vent 33, a connection 33a to the furnace is provided which discharges the gases to some point in the furnace 5 where the temperature is high enough to deodorize these gases. In the form shown, the gases pass downward through the baffle 67 and are discharged into the furnace at the lower end of the baffle. The excess is all ultimately discharged from the stack 69. The amount of gases taken off the furnace through 5, and the regulation of the pressure in casing 27 are effected exactly as in the form of Fig. 1.

What I claim is:

1. In apparatus of the kind described, the combination of a drying and pulverizing mill, a furnace, a duct from the furnace to the mill to supply drying gases, a mixing device, means to deliver to the mixing device raw wet material 20 to be treated, means to deliver to the mixing device treated dried material to be mixed in the mixing device with the raw material, a separator, a fan, a duct carrying the mixed material from the mixing device to the mill, a duct to convey 25 the gases and material from the mill to the separator, means to conduct the gases from the separator to the inlet of the fan, a duct from the outlet of the fan to the mixing device, damper means in the duct to the mixing device, and damper 30 means in the duct from the mixing device, whereby the pressure in the mixing device can be adjusted to a point differing slightly from atmosphere.

2. Apparatus in accordance with claim 1, and 35 further comprising means automatically adjusting the position of the damper in the duct leading to the mixer responsively to pressure changes in the mixer, to keep such pressure slightly below atmospheric.

3. Apparatus in accordance with claim 1, and 40 further comprising means automatically adjusting the position of the damper in the duct leading from the mixer responsively to temperature changes in the gases coming from the fan.

4. Apparatus in accordance with claim 1, and 45 further comprising means automatically adjusting the position of the damper in the duct leading to the mixer responsively to pressure changes in the mixer, and means automatically adjusting 50 the position of the damper in the duct leading from the mixer to temperature changes in the gases coming from the fan.

5. Apparatus in accordance with claim 1, and 55 further comprising means responsive to pressure conditions in the mixing device to open further the damper in the duct leading to the mixing device when the pressure in the mixing device falls below a predetermined point, and to move it in a closing direction when such pressure falls below a predetermined point, and means responsive 60 to temperature conditions of the gases leaving the fan to move the damper in the duct leaving the mixing device in an opening direction when said temperature falls below a predetermined point, and to move it in a closing direction 65 when it rises above a predetermined point.

ALFRED R. SMITH.
